UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

PRINTING PLATE MOLD

Application filed April 6, 1929. Serial No. 353,201.

This invention relates to a mold for casting a printing plate adapted to be held down on a printing cylinder at the longitudinal edges of the plate. The principal objects of 5 the invention are to provide the plate with means to facilitate holding down the straight edges and prevent their bulging out so as to imprint an excessively black impression on the paper, and also to avoid the possibility of breakage of the edge of the plate due to its 10 pounding back and forth repeatedly. Other objects and advantages of this invention will appear hereinafter.

Reference is to be had to the accompanying 15 drawings in which

Fig. 1 is a plan of a printing cylinder, partly in section, showing the cast plate;

Fig. 2 is an enlarged view of the same;

Fig. 3 is a sectional view on the line 3—3 20 of Fig. 2, and

Fig. 4 is a transverse sectional view of the edge of a casting mold in which such a printing plate is cast.

Printing plates usually are held on the 25 printing cylinders by end clamps only. These press against the semi-circular ends of the plates. The edges of the plate which are straight and parallel with the axis of the printing cylinder are not clamped. The result is that at high running speeds there is 30 a tendency for the center portions of these straight edges to be thrown out away from the cylinder by centrifugal force. This bulges out the edges of the plate and the part 35 which is necessarily farther away from the center of the cylinder than the rest of the plate bears against the paper on the impression cylinder with excessive force and very 40 dark printing results. The repetition of this action of pressing the edges of the plates 45 back against the cylinder as they pass through the impression, then throwing them out by centrifugal force, results in fatigue of the metal and sometimes a piece breaks out of 50 the edge of the plate. This is apt to cause considerable damage. Besides the centrifugal action just described, the bowing out of 55 the edges of the plates is apt to be caused or increased by the setting in of the clamps on 60 both ends of the plate. The natural ten-

dency of a man working on a high speed 55 press is to keep pulling his clamps tighter so that the plate will not fly off, thus accentuating the bowing outwardly of the edges of the plate.

In order to prevent these difficulties, I provide each plate 10, in addition to its holding means at its semicircular ends, with a recess 11 in each straight edge, preferably about 60 half way between the ends. I also provide 65 margin bars 12 extending along the straight edges of the plates with two tongues 13 on opposite sides, each one extending into a recess 11 in the plate adjacent thereto, I have shown these tongues as of considerable length 65 so as to hold the plates down and as having considerable clearance in the recesses at the ends. These tongues obviously are used in addition to the clamping means and the center clips 14 and margin rings 15 ordinarily 70 employed.

I have shown in Fig. 4 how these recesses 11 can be formed in casting the plates. In this Figure the back 16 and the core 17 are formed as usual, as is the matrix bar 18 and the 75 matrix 19. On the matrix clip 20, however, there is an additional feature in the form of a projecting tongue 21 which is properly sized and located in the mold and extends longitudinally along the edge thereof. It will be 80 obvious that this tongue projects into the plate 10 being cast so as to form a longitudinal recess 11 along the edge thereof and that there is nothing about its shape to prevent the taking of the matrix clip out of the mold after 85 the casting is completed.

It will be seen that by providing the casting molds with this simple additional feature and introducing the margin bars 12 with their tongues on the plate cylinders, the difficulties which have been described above are 90 entirely eliminated.

No claim is made herein to the features of the printing plate itself or the way of holding it on the printing cylinder because these 95 features constitute the subject-matter of my divisional application Serial No. 507,833, filed January 10, 1931.

Although I have illustrated and described 100 only one form of the invention I am aware of

the fact that modifications can be made therein by any person skilled in the art without departing from the scope of the invention as expressed in the claim. Therefore, I do not 5 wish to be limited to the exact form of construction herein shown and described, but what I claim is:—

In a mold for casting a stereotype printing plate, the combination with the core and back, 10 of a matrix clip having a tongue projecting tangentially into the mold cavity and extending longitudinally thereof between the back and the core.

In testimony whereof I have hereunto affixed my signature.

HENRY A. WISE WOOD.
